UNITED STATES PATENT OFFICE

2,472,021

PREASSEMBLED IMPEDANCE UNIT

Donald H. Mitchell, Chicago, Ill., assignor to
Motorola, Inc., a corporation of IllinoisOriginal application February 20, 1942, Serial No.
431,722. Divided and this application February
21, 1945, Serial No. 579,003

2 Claims. (Cl. 250—16)

1

This invention relates to preassembled impedance units of the type suitable for use as a component of an electrical apparatus having connection terminals arranged in a generally arcuate path and, while it is of general application, it is particularly suitable for embodiment in a unit to be mounted directly on the base of a vacuum-tube socket and is described herein in such an application. This application is a division of a pending application, Serial No. 431,722, filed February 20, 1942, United States Patent 2,439,408, and entitled "Portable radio device."

It is well known that radio apparatus generally comprises a chassis or frame member on which are mounted a number of vacuum-tube sockets for receiving replaceable vacuum tubes and a great number of circuit elements including resistors, condensers, and inductors. It is also well known that the assembling, mounting and wiring of these many circuit elements is a time-consuming operation and involves extensive and complicated wiring networks. These networks not only detract from the appearance of the apparatus but impede the repair and replacement of circuit elements and also, due to the lengths of the wiring connections, introduce undesired impedance and admittance into the circuit of the apparatus, particularly at high frequencies. It is also well known that the assembly of such radio apparatus is generally done by relatively unskilled employees, which tends to aggravate all of the factors discussed.

It is an object of the invention, therefore, to provide a new and improved preassembled impedance unit by means of which one or more of the above-mentioned problems of assembling radio or other electrical apparatus may be satisfactorily solved.

It is another object of the invention to provide a new and improved preassembled impedance unit which permits preassembly by automatic machinery of a substantial portion of the circuit elements of electrical apparatus, such as resistors, condensers and inductors comprised in the apparatus.

It is a further object of the invention to provide a new and improved preassembled impedance unit which is simple and compact and economical in construction and by means of which the lengths of the connecting conductors required in the wiring of associated electrical apparatus may be reduced to a minimum.

In accordance with the invention a preassembled impedance unit for use as a component

2

of an electrical apparatus having connection terminals arranged in a generally arcuate path comprises a generally cylindrical container and a plurality of impedance elements of predetermined values fixedly arranged around the periphery of the container and insulatedly supported therefrom and having connection terminals extending therefrom. The connection terminals of the unit are arranged to be disposed in proximity to their respective connection terminals of the apparatus. For a better understanding of the invention, together with other and further objects thereof, reference is had to the following description taken in connection with the accompanying drawings while its scope will be pointed out in the appended claims.

Referring now to the drawings, Fig. 1 is an exploded perspective view of a preassembled impedance unit embodying the invention; Fig. 2 is a cross-sectional view of the apparatus of Fig. 1; Fig. 3 is a longitudinal section of the device of Fig. 1 as applied to a vacuum-tube socket, while Figs. 4 and 5 are top and side views, respectively, of the assembled device of Fig. 1.

Referring now to Figs. 1 and 2 of the drawings, there is illustrated a preassembled impedance unit for use as a component of an electrical apparatus, such as a vacuum-tube socket 94, having a cylindrical body portion 92 and a plurality of connection terminals 98 arranged in a generally arcuate path concentric with the body portion 92 and projecting from one end of the socket. The impedance unit consists of a generally cylindrical, preferably annular, open-ended container member 101 of insulation material and of channel-shaped cross section, the open end thereof being closed or sealed by a flat ring-shaped closure member 103 of insulation material such as fibre. Around the periphery of the container 101, that is, within the annular channel thereof, are fixedly arranged a plurality of impedance elements such as resistors R and condensers C, which are of predetermined values and electrically connected together in a predetermined circuit arrangement to provide the desired circuit characteristics for the associated apparatus, for example a tube T1 disposed in the socket (Fig. 3). Connections 105 for connecting the resistors and condensers to the connection terminals 98 extend outwardly from the impedance unit 99 through the bottom wall thereof.

Usually not all of the connections from the impedance unit are to be connected with the socket connection terminals 98 but some of them are to be connected to other portions of asso-

ciated apparatus. These other connections, therefore, are in the form of connection lugs 105a (Figs. 4 and 5) secured to the container member 101 to facilitate their connections with any other part of the associated apparatus. With the condensers C and resistors R in position within the container member 101, a mass of suitable impregnating insulation material, such as wax or the like and indicated at W, is disposed in the container 101, for example poured into the upper open end thereof, the hardening of the wax embedding the elements, retaining them in fixed positions, and protecting them against any short circuiting or exposure to the atmosphere. The closure member 102 is then glued or otherwise suitably secured to the open end of the container 101. To facilitate the connection of the impedance unit 99 to its associated circuit elements and to indicate the manner in which the resistor and condenser elements are connected therein, a circuit diagram for the unit, indicated at 100 (Fig. 5) is applied on the outer periphery of the container 101.

The impedance unit 99 also includes provisions for mounting it from the cylindrical body portion of an associated electrical apparatus and concentric therewith. Specifically, its inner opening is proportioned so that it may be mounted and fitted directly on the body portion 92 of the cylindrical tube socket 94. As indicated in Fig. 3, the socket 94 is supported from a chassis or frame member 89 and it is adapted to receive a tube T₁ and to support a cylindrical shield can 121.

In the assembly of the impedance unit 99 on the tube socket 94, the soldering of the connections 105 with the connection terminals 98 of the socket 94 holds the impedance unit 99 in a fixed assembled position on the socket. In order to retain the impedance unit 99 in the assembly position during the soldering operation, it may be cemented or glued to the chassis 89 or to an associated element thereof. The elements within the unit 99 are so arranged that, when the unit 99 is mounted in an assembly position on the socket 94, the connection terminals 105 extending therefrom are arranged in proximity to their respective connection terminals 98 of the tube socket. With this arrangement the interconnection of the impedance unit 99 and the tube socket 94 is of maximum simplicity and the connection leads are as short as possible.

Although the impedance unit of the invention has been described with reference to a particular application thereof, it is readily apparent that it is not limited to this one application but can be constructed within the scope of this invention for use generally as a component of electrical apparatus. Considerable difficulty is usually encountered in handling and assembling of the condenser and resistor elements in a radio apparatus. By virtue of the compact and insulated assembly of the elements in the impedance unit 99, this unit can be conveniently arranged relative to any desired circuit in which it is used and connections

made therefrom to other portions of such circuit. Individual handling and assembling of the resistor and condenser elements and their connections into the radio circuit is thus entirely eliminated, thereby decreasing the time usually required in making the connections and providing for neater appearing and more secure electrical connections.

While there has been described what is at present considered to be the preferred embodiment of the invention, it will be apparent to those skilled in the art that various changes and modifications may be made therein without departing from the spirit or scope of the invention.

What is claimed as new is:

1. In an electrical apparatus including one or more electron tube sockets, each of said sockets having a cylindrical body portion adapted to receive prongs of an electron tube, and a plurality of axially extending connection terminals arranged in generally concentric relation to said body portion, a preassembled impedance unit for use as a component of said apparatus comprising an annular container having an inner opening of such size as to fit closely about said body portion of a tube socket, a plurality of impedance elements of predetermined values fixedly arranged within said container and insulatedly supported thereby, and electrical conductors extending from said impedance elements out of said container, said container having an axial dimension not greater than the overall axial dimension of said tube socket body portion and said connection terminals, whereby said impedance unit may be disposed within the axial limits of and surrounding the space occupied by said socket body portion and said terminals.

2. A preassembled impedance unit as defined in claim 1, wherein certain of said electrical conductors leading from said impedance elements are arranged to be disposed in proximity to certain of the connection terminals of the tube socket with which said unit is associated, so as to facilitate electrical connection thereto.

DONALD H. MITCHELL.
